DESIGN FOR A KITCHEN TABLE

Alfons Bach, Stamford, Conn., assignor to National Manufacturing Corporation, New York, N. Y., a corporation of Connecticut

Application February 7, 1946, Serial No. 126,365

Term of patent 14 years

(Cl. D33—14)

To all whom it may concern:

Be it known that I, Alfons Bach, a citizen of the United States and residing at Stamford, in the county of Fairfield and State of Connecticut, have invented a new, original, and ornamental Design for a Kitchen Table, of which the following is a specification, reference being had to the accompanying drawings, forming part thereof and in which

Fig. 1 is a top perspective view of a kitchen table showing my new design, and

Fig. 2 is a bottom plan view of the same table.

I claim:

The ornamental design for a kitchen table, substantially as shown.

ALFONS BACH.
